E. W. SZWAJKART

HOLDER AND DISPENSER FOR DENTAL STOPPING

Filed Nov. 21, 1923

By *Oliver C. O'Brien*
Attorney

UNITED STATES PATENT OFFICE.

EUGENE W. SZWAJKART, OF CHICAGO, ILLINOIS.

HOLDER AND DISPENSER FOR DENTAL STOPPING.

Application filed November 21, 1923. Serial No. 676,123.

To all whom it may concern:

Be it known that I, EUGENE W. SZWAJKART, a citizen of the United States, residing at Chicago, in the county of Cook and State 5 of Illinois, have invented certain new and useful Improvements in Holders and Dispensers for Dental Stopping, of which the following is a specification.

This invention relates to a combination 10 holding and dispensing implement specifically adapted for the holding and dispensing of dental stopping, whereby the same may be placed within the implement and fed outwardly therefrom when desired, the 15 device also comprising a cutter for cutting off a sufficient length of the stopping whenever the same is to be used. It will thus be seen that an implement of this character will overcome the necessity of holding the 20 stopping in the hand and cutting off the desired length, by a knife or other implement.

The primary object of the present invention resides in the provision of an article 25 of the above character that may be manufactured and marketed at a relatively small cost, the device being extremely simple of construction, the same comprising but few parts and these correlated with each 30 other in such a manner as to reduce the possibility of disarrangement to a minimum.

With the above and other objects in view 35 as the nature of the invention will be better understood, the same comprises the novel form, combination and arrangement of parts hereinafter more fully described, shown in the accompanying drawing and claimed.

In the drawing wherein there is shown the most practical embodiment of the invention 40 with which I am at this time familiar, and wherein like reference characters indicate corresponding parts throughout the different views,

Figure 1 is a side elevational view of a 45 combined holder and dispenser for dental stopping, constructed in accordance with the present invention,

Figure 2 is an edge view of the outlet end 50 of the holder, the stopping cutter element being shown as slightly raised for allowing the stopping to be fed from its holder,

Figure 3 is an elevational view of one 55 of the longitudinal edges of said holder, this edge being provided with a relatively elongated longitudinal slot through which an

element that is carried by the sliding stopping carrying table extends for allowing this table to be slid toward the open end of the holder for manifestly discharging the stopping therefrom and for allowing the same to be cut the desired length.

Figure 4 is a detail longitudinal sectional view of the article, and

Figure 5 is a perspective of the before mentioned sliding stopping carrying table. 65

Now having particular reference to the drawing, my novel stopping holder and dispenser embodies a relatively elongated and flat metallic receptacle 5 open at its opposite ends and provided at one end with a hinged snap cover of suitable design and 70 designated 6. The opposite open end of this receptacle is formed at its vertical edges with inwardly bent guide flanges 7. These guide flanges 7—7 terminate slightly above 75 the lower longitudinal wall of the receptacle 5 for allowing the stopping to be fed therethrough in a manner hereinafter to be more fully described.

Disposed for longitudinal sliding movement within the receptacle 5 and upon the lower narrow bottom wall thereof is a relatively elongated stopping carrying table 8 that is formed with either one or two longitudinal concave channels 9 for the reception 80 of the sticks of stopping material, the end of this table remote from the flanged open end of the receptacle 5 being equipped with a hinged clipper member 10 whereby the innermost stoppings may be secured to the 85 table. The wall of the receptacle upon which said table 8 slides, is formed throughout almost its entire length with a slot 11 through which extends a thumb piece 12 carried by the table 8 and adapted to be engaged by the thumb of the dentist for manifestly forcing the stopping outwardly 90 through the flanged open end of the receptacle. 95

Guided for vertical sliding movement between the before mentioned flanges 7—7 is a cutter member 12 that is formed at its upper end with a finger piece 13 for facilitating the raising and lowering of said knife, it being of course obvious that after 100 the stopping has been fed outwardly from the receptacle, this cutter element 12 may be forced downwardly for manifestly cutting off sufficient length of the stopping.

From the above it will thus be seen that 110

I have provided a highly novel holding and dispensing article for dental stopping and one that will I believe, meet with all of the requirements for a successful commercial use.

Minor changes may be made within the invention without departing from the spirit and scope of the appended claims.

Having thus described my invention, what I claim as new and desire to secure by Letters Patent is:—

1. A device of the class described comprising an elongated receptacle open at its opposite ends, a hinged closure for one of the ends thereof, a cutting member adapted for slidable movement in the other end of the receptacle, the bottom of said receptacle having a longitudinally extending slot provided therein, an article supporting table slidably supported in the bottom of said receptacle, means at one end thereof for engagement with the article for holding the same on the table, and means extending from the bottom

of said table through said slot for feeding the article on the table to said cutter. 25

2. A device of the class described comprising an elongated receptacle open at its opposite ends, a hinged closure for one of the ends of the same, a cutting member adapted for slidable movement in the other end of the receptacle, the bottom of said receptacle having a longitudinally extending slot provided therein, an article supporting table slidably supported in the bottom of said receptacle, a hinged clip carried by the rear end of said table and adapted for engagement with the rear portion of the article supported on the table for holding the same in position thereon, and a handle extending from the bottom of said table adjacent said hinged clip through said slot for feeding the forward end of the article through the cutter. 30 35 40

In testimony whereof I affix my signature.

DR. EUGENE W. SZWAJKART.
